ELECTRIC SWITCH

William C. Crimmins, Marion, Ind., assignor to
Delta Electric Company, Marion, Ind., a cor-
poration of Indiana

Application March 28, 1938, Serial No. 198,422

1 Claim. (Cl. 200—153)

This invention relates to electric switches.

One of the primary objects of the present invention is to provide an improved and simplified switch structure in which a minimum number of parts are utilized, thereby providing a switch structure which is economical to manufacture.

A further object of the present invention is to provide an improved structure for mounting a sliding button on an escutcheon plate, whereby the button may be readily moved relative to the plate with a minimum of wear on the engaging parts.

Other objects of the invention will become apparent from the following specification, the drawing relating thereto, and from the claim hereinafter set forth.

In the drawing in which like numerals are used to designate like parts in the several views throughout:

Figure 1 is a front elevational view of a switch structure embodying features of the present invention;

Fig. 2 is a cross-sectional view taken substantially along the line 2—2 of Fig. 1;

Fig. 3 is a view similar to Fig. 2 illustrating the parts in a different position;

Fig. 4 is a cross-sectional view taken substantially along the line 4—4 of Fig. 1;

Figs. 5, 6, and 7 are enlarged perspective views of certain of the elements used in the switch structure according to the present invention;

Fig. 8 is a longitudinal cross-sectional view of a modified form of button having the attaching clips molded therein; and,

Fig. 9 is a cross-sectional view taken substantially along the line 9—9 of Fig. 8.

In the switch of the present invention the contact terminals are mounted directly to the escutcheon plate, and a sliding button is slidably mounted directly to the escutcheon plate, to complete and break the circuit between the terminal members. Means are provided for slidably mounting the button relative to the escutcheon plate which includes yoke members fixed to the button having bent ends which engage slide plates mounted within recesses in the back of the escutcheon plate. An easy sliding movement is thereby insured for the button relative to the plate, and the construction is such that the engaging parts do not wear away, so that the life of the switch is considerably lengthened.

Referring to the drawing for a more detailed description of the invention, and referring particularly to Figs. 1 to 7, an electric switch structure is illustrated which includes an escutcheon

plate 10 of suitable design having openings 12 therethrough, through which attaching members such as screws are adapted to extend for attaching the switch to a supporting body. The escutcheon plate 10 is preferably made of a molded plastic material. Metal contact terminal members 14 are fixed directly to the escutcheon plate 10 in spaced relation to each other and preferably aligned along the longitudinal axis of the plate 10. The members 14 extend completely through the plate and terminate substantially flush with the forward face thereof. Lead wires 16 are suitably attached to the terminals 14 in the usual way. The plate member 10 has elongated substantially parallel recesses 18 formed in the rear face thereof adjacent the terminals 14; and slots 20 are provided through the plate member 10 communicating with and extending along the inner edges of the recesses 18.

In order to make and break contact between the terminals 14, a button 22 is slidably mounted directly on the front face of the escutcheon plate 10. The button, which is also preferably formed of a suitable molded plastic, has a longitudinally extending recess 24 formed on the inner face 25 thereof, which is adapted to receive therein an elongated metal contact member 26. The contact member 26 has spaced contact points 28 formed thereon and has its ends 30 bent at an angle so that the bent ends 30 engage the end 30 walls of the recess 24 and guide the contact member 26 in its movement within the recess. Another substantially cylindrical recess 32 is provided in the button 22 at substantially mid point which is adapted to receive a coil spring 34 therein. The coil spring 34 bears against the adjacent face of the contact member 26 and urges it against the adjacent face of the escutcheon plate 10 so that when the circuit is closed, the contact points 28 are resiliently urged into contact with the terminals 14, as shown in Fig. 3. The spring 34 also permits movement of the contact member 26 away from contact with the terminal as the button is slid along the escutcheon plate.

In order to slidably mount the button 22 directly on the escutcheon plate so that positive sliding action may be obtained without undue wear of the parts and without causing looseness between the button and the escutcheon plate, yoke members 40, preferably of metal are fixed to the button 22 and extend longitudinally thereof and through the button. The yoke member 40 may be molded in the button when the button is formed, or they may be placed through open-

ings which are formed in the button either during the molding operation or afterwards. In this embodiment, preformed parallel openings are provided through the button to receive therein the legs of the yoke members 40 along each side of the button. Longitudinally extending grooves 41 communicate with the parallel openings so that when the yoke members 40 are placed in the openings the bases of the yoke members will lie within the grooves 41 with the outer edges of the yoke members substantially flush with the outer surface of the button.

The ends 42 of the yokes are adapted to extend through the slots 20 adjacent the inner edges 15 of the recesses 18. Metal slide plates 44 of substantially the same size and configuration as the recesses 18 are disposed in the recesses 18 and may be suitably fixed therein, as by a press fit. The ends 42 are then bent outwardly, as best shown in Figs. 4 and 5, and are adapted to slidably engage the slide plates 44. As the button 20 is slid longitudinally of the escutcheon plate 10, the bent portions 42 engage and slide over the slide plates 44, thereby providing a structure 25 by which the button 22 is positively held in position relative to the escutcheon plate and by which relatively easy sliding of the button is obtained. The metal slide plates further afford a construction which does not rapidly wear away in 30 use, and consequently the switch has a relatively long life.

In Fig. 3 the parts are illustrated when the switch is in its on position, or when the circuit is closed, in which event the contact points 28 of 35 the contact member 26 engage in complementary cone-shaped recesses in the inner ends of the terminals 14. When the button is moved to the position illustrated in Fig. 2 the switch is in its off position, or the circuit is open, in which event 40 the contact between the terminals 14 is broken, and complementary cone-shaped recesses are provided in the escutcheon plate for the reception of the contact points 28 so as to prevent inadvertent displacement of the button. As the 45 button is slid from one position to the other the bent ends 42 of the yoke member 40 slide along the slide plate 44 and maintain the button 22 in a firm position relative to the escutcheon plate

10, while permitting sliding movement therebetween.

In Figs. 8 and 9, a modified form of button is illustrated in which the yoke members 40 are molded directly in the button 22 when the button is formed. In this embodiment the yoke member 40 is of less depth than the yoke member 40 in the embodiment described above, and has upwardly and outwardly tapering side edges 43 on those parts of the yoke members which 10 are embedded within the plastic button. These tapering side edges 43 assist in keeping the yoke members in place after the yoke members are molded into the buttons. The lower edge of the base of each of the yoke members lies substantially flush with the lower face of the button. The ends of the legs of the yokes are adapted to extend through the slots 20 adjacent the inner edges of the recesses 18, when the button is assembled, and be bent outwardly as indicated at 20 42 in the embodiment described above.

Formal changes may be made in the specific embodiment of the invention described without departing from the spirit and substance of the invention, the scope of which is commensurate 25 with the appended claim.

What is claimed is:

An electric switch structure comprising an escutcheon plate, electric terminal members fixed directly to said plate, said escutcheon plate having substantially parallel elongated recesses formed in the rear face thereof adjacent said terminal members, a slide plate disposed within each of said recesses, a button on the forward face of said escutcheon plate slidable relative 35 thereon, a contact member resiliently mounted within said button for completing the circuit between said terminals when the button is in one position, and means for slidably mounting said button directly on said plate, said last-named 40 means including yoke members fixed to said button and extending through said escutcheon plate adjacent said slide plates, the ends of said yoke members being bent to slidably engage said slide plates and thereby slidably fix said button relative to said escutcheon plate.

CERTIFICATE OF CORRECTION.

Patent No. 2,207,457.

July 9, 1940.

WILLIAM C. CRIMMINS.

It is hereby certified that error appears in the printed specification of the above numbered patent requiring correction as follows: Page 2, second column, line 36, in the claim, for the word "thereon" read --thereto--; and that the said Letters Patent should be read with this correction therein that the same may conform to the record of the case in the Patent Office.

Signed and sealed this 10th day of September, A. D. 1940.
